[57] CLAIM

The ornamental design for an electrically heated tool for applying an anchoring fastener, as shown and described.

DESCRIPTION

FIG. 1 is a top, front and right side perspective view of an electrically heated tool for applying an anchoring fastener showing our new design;

FIG. 2 is a top plan view thereof;

FIG. 3 is a right side elevational view thereof, the left side is identical thereto;

FIG. 4 is a bottom plan view thereof;

FIG. 5 is a front elevational view thereof; and

FIG. 6 is a rear elevational view thereof.

The broken line showing of a power cord fragment in FIGS. 1-4 is for illustrative purposes only and forms no part of the claimed design.

FIG. 1

FIG. 2

FIG. 3

FIG. 4

FIG. 5

FIG. 6
